D. F. STOCKBRIDGE,
CONCRETE LINTEL.
APPLICATION FILED OCT. 2, 1918.

1,364,216.

Patented Jan. 4, 1921.

UNITED STATES PATENT OFFICE.

DAVID F. STOCKBRIDGE, OF OKLAHOMA, OKLAHOMA.

CONCRETE LINTEL.

1,364,216.

Specification of Letters Patent.

Patented Jan. 4, 1921.

Application filed October 2, 1918. Serial No. 256,492.

To all whom it may concern:

Be it known that I, DAVID F. STOCKBRIDGE, a citizen of the United States, residing at Oklahoma, in the county of Oklahoma and State of Oklahoma, have invented a new and useful Concrete Lintel, of which the following is a specification.

This invention relates to a concrete lintel particularly designed to span a window or other opening in a masonry wall. In the term "masonry wall" I include any wall built up of separate blocks, such as bricks or prepared stone.

In such walls it is common to provide a facing in front of the lintel, and the general object of my invention is to provide an improved lintel in which novel and effective provision is made for supporting such a facing.

As far as I am advised, it has not been possible to support a facing from any concrete lintel heretofore used, except by securing an angle iron thereto or by making other special provision requiring an increase in 25 both labor and material. In my improved lintel the design is such that the facing is supported directly by the lintel, which is formed as a single integral structure. My invention also relates to the special provision 30 made for sustaining the lower course of the facing thus supported.

My invention further relates to certain arrangements and combinations of parts which will be hereinafter described and more particularly pointed out in the appended claims.

A preferred form of my invention and certain modifications thereof are shown in the drawings, in which—

Figure 1 is a front view of a portion of a 40 wall in which my improved lintel is used;

Fig. 2 is a vertical sectional view taken along the line 2—2 in Fig. 1;

Fig. 3 is a horizontal section taken along the line 3—3 in Fig. 2;

Fig. 4 is an enlarged detail front elevation 45 showing the means for supporting the lower course of the facing from the headers;

Fig. 5 is a vertical sectional view showing a modification;

Fig. 6 is a detail front elevation showing a 50 second modification, and

Figs. 7 and 8 are vertical sectional views taken along the lines 7—7 and 8—8 in Fig. 6 respectively.

Referring to Fig. 1, I have shown a portion of a masonry structure 10 having a win-

dow opening 11 therein. The lintel 12 is indicated in dotted lines in Fig. 1, and is shown in vertical section in Fig. 2.

This lintel 12 consists of an integral concrete beam extending across the opening in the wall and having its ends embedded in and supported by the masonry structure. The lintel may be strengthened by the provision of suitable steel reinforcement 13 if 65 desired. The thickness of the lintel is commonly less than that of the wall, thereby providing a space for a facing in front of the lintel.

A longitudinally extending recess 14 is 70 formed in the lower portion of the lintel, but spaced somewhat from the lower face of the lintel by a flange 14^a. This recess 14 is of such dimensions that it can receive the rear ends of blocks or headers 15 which are suitably em- 75 bedded therein and project outward to form a portion of the facing being supported by the flange 14^a. The outer ends of these headers may project beyond the face of the wall to give an ornamental finish or they may be 80 flush with the wall, as indicated by the dotted line in Fig. 2.

The lower course of the facing is sustained by the headers in any convenient manner. In Fig. 2 I have shown a construction in 85 which the lower course is formed of half bricks or bats 16 supported from the headers 14 by tie-rods 17 embedded in the mortar between the bats and between the headers, and provided at their lower ends with 90 enlarged heads or washers of sufficient size to engage the bats on either side. At its upper end each rod may be bent over, as indicated in Fig. 4, to engage the top of a header. The upper courses 18 of the facing 95 rest directly upon the headers 15.

With this construction it will be seen that the facing entirely conceals the concrete lintel, and at the same time is firmly supported thereby without the use of expensive structural steel or other special construction. 100

In constructing the facing above described, it is convenient to use a temporary floor board 19 supported against the lower face of the lintel, upon which the lower 105 course and the headers are built up, the tie-rods 17 being inserted as the blocks are laid. After the mortar has set, the tie-rods are bent down over the headers and the upper courses are added, thus forming the complete facing.

In Fig. 5 I have indicated the use of

strips of expanded metal 20 between the headers and bats in place of the headed tie-rods previously described. The strips may be extended at their upper or lower ends, 5 and the ends may be bent around the adjacent blocks if desired.

In Figs. 6, 7 and 8, I have shown a construction in which the tie-rods and metal strips are omitted. In this construction the 10 headers 15 are alternately disposed, being separated by vertically extending blocks 21 called "soldiers." The soldiers also alternate with the bats 16 and wherever a soldier is used an additional short block or bat 22 15 replaces the rear portion of the omitted header. By thus alternating the headers and soldiers, the two lower courses are firmly bonded together and are firmly secured to the lintel 12.

Having fully described the construction and use of my improved lintel, it will be evident that it possesses many distinct advantages, including simplicity of construction and economy in manufacture. It will also 25 be evident that changes and modifications can be made therein without departing from the spirit and scope of my invention as set forth in the claims and I do not wish to be otherwise limited to the details herein disclosed, but what I claim is—

1. As an article of manufacture for use in a faced masonry wall having an opening, a lintel formed as a single piece of concrete adapted to be embedded at its ends in said 30 masonry and to extend across said opening as a self-supporting rigid unit, said lintel having its outer face substantially vertical and parallel with the outer face of the wall in which it is used, and having a longitudinally 35 extending recess therein spaced from both the upper and lower edges of said lintel, and effective to receive portions of bricks of standard size forming a facing and to engage both the upper and lower faces of 40 said bricks, thus independently supporting said facing on the vertical recessed face of said lintel.

2. As an article of manufacture, a concrete lintel for a faced masonry wall comprising a reinforced concrete beam of less 50 thickness than said wall and having a longitudinally extended recess in the front face thereof adjacent the lower edge of said lintel but spaced therefrom, said recess being adapted to receive the rear ends of headers 55 supporting a facing, and the combined thickness of the lintel and facing being approximately equal to the normal thickness of the wall.

3. In a masonry wall having an opening, 60 a concrete lintel covering said opening and having a longitudinally extended recess in the front face thereof, headers embedded in said recess and forming a portion of a facing, an additional portion of said facing disposed below said headers, and means to support said lower portion from said headers.

4. In a masonry wall having an opening, 70 a concrete lintel covering said opening and having a longitudinally extended recess in the front face thereof, headers embedded in said recess and forming a portion of a facing, an additional portion of said facing disposed below said headers, and means to support said lower portion from said headers, 75 said means being embedded in the mortar between said headers.

5. In a masonry wall having an opening, 80 a concrete lintel covering said opening and having a longitudinally extended recess in the front face thereof, headers embedded in said recess and forming a portion of a facing, an additional portion of said facing disposed below said headers, and means to support said lower portion from said headers, 85 said headers and said lower portion being composed of separate blocks and said means comprising tie-rods embedded in the mortar between adjacent blocks, said rods being supported by said headers and themselves 90 supporting the lower blocks.

In testimony whereof I have hereunto affixed my signature.

DAVID F. STOCKBRIDGE.
